(57) **CLAIM**

The ornamental design for a walkie talkie, as shown and described.

DESCRIPTION

FIG. 1 is a front elevational view of a walkie talkie showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is an enlarged view of portion 7 shown in FIG. 6;

FIG. 8 is a perspective view thereof;

FIG. 9 is a second perspective view thereof; and,

FIG. 10 is a third perspective view thereof.

The broken lines used to indicate the enlarged portion in FIGS. 6 and 7 form no part of the claimed design.
